J. F. VEACO

METHOD OF MANUFACTURING SOUNDING BOARDS FOR MUSICAL INSTRUMENTS

Filed Oct. 22, 1921

UNITED STATES PATENT OFFICE.

JAMES FREDERICK VEACO, OF BERKELEY, CALIFORNIA.

METHOD OF MANUFACTURING SOUNDING BOARDS FOR MUSICAL INSTRUMENTS.

Application filed October 22, 1921. Serial No. 509,555.

To all whom it may concern:

Be it known that I, JAMES FREDERICK VEACO, a citizen of the United States, residing at Berkeley, in the county of Alameda, State of California, have invented a new and useful Method of Manufacturing Sound- 5
ing Boards for Musical Instruments, of which the following is a specification, in such full and clear terms as will enable those skilled in the art to construct and use the same.

This invention relates to a method of making sounding boards for musical instruments and its object is to lighten the load on such sounding boards.

A further object of the invention is to lighten the weight of the sounding board and to improve the tone.

A further object of the invention is to make the sounding board stronger and to give it a better and more permanent crown, while at the same time making it more responsive to the string vibrations, whereby a rounder and fuller tone is produced.

A further object of the invention is to produce an initial strain in the sounding board which will render the tone better than the ordinary sounding board.

Other objects of the invention will appear as the description proceeds.

An embodiment of the invention is shown in the accompanying drawings in which the same reference numeral is applied to the same portion throughout, but I am aware that there may be modifications thereof.

Fig. 1 is a side elevation of the apparatus used in the manufacture of the sounding board.

Fig. 2 is a side elevation of the apparatus used in the manufacture of the sounding board looking in right angles of Figure 1.

Fig. 3 is a side elevation, and

Fig. 4 a plan view of one of the clamps for holding one of the ribs during the stretching operations.

Fig. 5 is a side elevation and

Fig. 6 a plan view of one of the clamps used at the opposite end of the ribs.

Fig. 7 is a view of the spring used for measuring the tension applied to the ribs during the stretching operations, and

Fig. 8 is a side elevation of the sounding board after it has been released from the press, showing the crown formed by the stretching of the ribs.

In producing a sounding board for musi-

cal instruments by this method, the sounding board is laid flat upon any suitable table. The ribs are then stretched nearly to their breaking point, whereupon they are glued 60 permanently to the sounding board. A suitable apparatus is applied to them to hold them tightly against the sounding board until the glue has had time to set, after which the strain on the ribs is released, and the 65 sounding board may be removed from the table upon which it was laid, whereupon the contraction of the ribs causes the board to be bent concave on the side the ribs are applied to, and owing to the initial stretching 70 given the ribs they will always retain the crown on the sounding board, since the crowning is due not to the bending of the ribs themselves which may in time cause a permanent set in them, but to the stretching 75 of the material which immediately places the sounding board itself in a state of compression as soon as the stretching of the ribs is released.

The apparatus used consists of a pair of 80 sawhorses 1 and 2 upon which a plurality of clamps 3 are placed. These clamps consist of heavy plates with upturned ends having open slots as indicated at 4, such a number of the clamps is used as may be required, 85 the number being dependent entirely upon the size and stiffness required in the sounding board.

These clamps are loosely laid upon the sawhorses so that they may be moved to any 90 desired position, and upon them is loosely placed a heavy flat board 5 which forms the table upon which the sounding board 6 is laid.

Yokes 7 in such number as may be desired 95 are secured to the edge of the board 5, and each yoke is provided with a screw 8, the object being to hold three or more beams 9 down against the ribs 10 while the glue is in process of setting, ordinarily requiring 100 18 to 24 hours.

A clamp 11 having two prongs 12 and 13 to embrace one end of the rib is used at one end of each of the ribs. This clamp has a yoke 14 surrounding its prongs 12 and 13, 105 and a screw 15 is used to tighten the prongs against the rib to hold it rigidly. This clamp also has side lugs 16 and 17 which engage the sides of the bars 3 adjacent the slots 4.

A somewhat similar clamp 18 is used at the other end of the ribs. It has two prongs

19 and 20 which embrace the ends of the ribs, while a yoke 21 with a set screw 22 affords the means for tightening the prongs 19 and 20 on the ribs. This clamp also has a threaded end 23 with a nut 24 thereon for placing a strain on the ribs.

A washer 25 is placed on the threaded rod end 23 and bears upon a heavy spring 26, the object being to provide means whereby 10 a given load may be applied to each rib by measuring the compression of each of the several springs used.

When the sounding board has been placed on the table 5, the ribs are placed thereon, 15 the clamps 11 and 18 are applied and the desired pressure is applied to each of the ribs, whereupon the glue is applied to the under side of the ribs and the screws 8 are operated to tighten the cross beams 9 down against 20 the ribs to hold them tightly in place until the glue has been set. When the glue has set between the ribs and sounding board, the clamps may be released and the ends of 25 the ribs may then be cut off the desired length, whereupon the sounding board will be bent as illustrated in Figure 8 with the ribs on the concave side.

In practice it has been found that it is 30 possible to make ordinary piano sounding boards crown sufficiently by using from six to ten ribs, each of which is strained up to about eight hundred pounds before being glued fast to the board.

This refers to ribs about three-eighths of 35 an inch thick and one inch wide. If heavier ribs are used the initial strain must be increased accordingly. The actual amount of lengthening of the ribs under the given strain is comparatively small for when the 40 elastic limit is reached the rib is likely to break with the application of very little additional stress. The wood used may be of any kind at present used in sounding boards, but some species of fir is most commonly 45 used for the ribs. The sounding boards are usually made up of several widths of board of the desired character glued together to produce a board of the desired width.

What I claim is as follows, but modifications may be made in the above particularly 50 described form of the invention within the purview thereof:

1. A method of producing sounding boards for musical instruments which comprises placing the sounding board upon a flat surface, placing the ribs thereover, stretching the ribs longitudinally, securing the ribs rigidly to the sounding board, and then releasing the strain upon the ribs.

2. A method of producing sounding boards 60 for musical instruments which comprises placing the sounding board upon a suitable surface, placing the ribs thereon, stretching the ribs, rigidly securing the ribs to the sounding board, and thereafter releasing the ribs from the stretching apparatus and cutting them the desired length.

3. A method of producing sounding boards for musical instruments which comprises placing the sounding board upon a suitable support, placing the ribs on the sounding board, stretching the ribs as may be desired, gluing the ribs to the sounding board, securing the ribs rigidly against movement until the glue has set, and thereafter releasing the ribs and cutting them the desired length.

4. A method of producing sounding boards for musical instruments which consists in stretching the ribs, securing them to the board in a stretched condition, and then removing the strain from the ribs whereby the board is permanently crowned.

5. A method of producing sounding boards for musical instruments which consists in stretching the ribs, securing them rigidly to the board throughout their length while they are stretched, and then removing the strain from the ribs whereby the board is crowned.

In testimony whereof I have hereunto set 90 my hand this 14th day of October, A. D. 1921.

JAMES FREDERICK VEACO.

Witness:

FRANKLIN S. BECKETT.
